UNITED STATES PATENT OFFICE.

GEORGE R. SMITH, OF ITHACA, NEW YORK.

RAILROAD-SWITCH.

Specification forming part of Letters Patent No. 20,959, dated July 20, 1858; Reissued December 17, 1867, No. 2,814.

To all whom it may concern:

Be it known that I, GEORGE RANDALL SMITH, of Ithaca, county of Tompkins, and State of New York, have invented a new and Improved Railroad-Switch; and I do hereby declare that the following is a full and exact description thereof, reference being had to the accompanying drawings and letters of reference marked thereon.

10 Figure 1, is a perspective view of the switch complete as attached to the truck. Letters *a*, *a*, represent the upright shaft, the lower end of which rests upon and turns in a metallic bed plate. Letter *b* is the pinion which is securely keyed to the lower extremity of the shaft *a*. Letter *c* is a rack of any required length in which the cogs of the pinion *b*, play. Letter *d*, is a cap-piece extending over both rack and pinion 15 to hold them down to their places. In the cap piece *d*, is a friction roller resting against the back of the rack *c*. Letters *e*, *e*, represent the rod extending from, and forming part of the rack *c*, with clamps clasping 20 the rails near their movable extremity. Letters *f*, *f*, *f* are the frame or standard (which should be made of iron) and supports the shaft *a*, and the circle *g*, *g*, on which circle the spring lever *h*, slides. The 25 spring lever *h*, is to turn the shaft *a*, and is securely attached to said shaft immediately above its bearings in the frame *f*, *f*, *f*. Letters *i*, *i*, *i*, represent slots in the upper surface of the circle *g*, *g*, into which the spring 30 lever *h*, drops when the rails are in opposition. The lever is held sufficiently firm in these slots by its own spring. The size of the slots should accurately correspond to the 35 size of the lever. Letters *k*, *k*, *k*, *k*, represent signals so attached to the upper extremity of the shaft *a*, *a*, as to exhibit to the approaching train the condition of the switch. Letter *l*, represents a signal light or lantern and is so constructed, as will be shown here- 40 after, as to show a white light when the switch and main truck are in opposition and to invariably show red light when the switch is turned to either side. Letters *s*, *s*, show the movable portion of the rails, and 45 *t*, *t*, *t*, *t*, *t*, *t*, the stationary track.

50 Fig. 2 letter *h* is a view of the spring lever.

Fig. 3, letters *b*, *c*, and *e*, *e*, is a separate view of the pinion and rack and its extending rod.

55

Fig. 4 letter *d*, is a sectional view of the cap piece.

The lamp or signal light above referred to is to be made four sided; two sides, opposite each other, to be of clear glass, and the other two sides of stained or red glass. The lantern is set upon the top of the shaft *a* and turns with it. The upper end of the shaft is to be made of the proper shape to fit accurately an oblong opening in the bottom 60 of the lamp. By this simple device it is impossible for any one to place the lamp either designedly or carelessly so that it shall deceive the approaching train.

The following are some of the advantages 65 claimed for this over other switches. It can be changed more rapidly than any other; it is sure to be fastened when the switch is changed. The strain being so nearly at the end or rest of the shaft does not rack the 70 switch so much as when lever power is used. The rack and pinion may be securely boxed from storm or dirt. Lastly economy, being less expensive and more durable than ordinary switches.

80

I claim—

1. The described rack and pinion at the base of a perpendicular rotating or partially rotating shaft, when combined with a spring lever, and a circle or segment of a circle; 85 said lever being fixed at right angles to said shaft, and playing on said circle or segment, and into slots in the same; and said segment or circle being horizontal.

2. Further I claim the above named combination when further combined with a signal lantern; which lantern revolves wholly or in part, when adjusted to the top of said shaft; said lantern having different colored glasses, and revolving on an axis drawn perpendicularly through the center of said lantern.
